ARTIST SKETCH BLOCK

Samuel Dovitch, New York, N. Y.

Application March 13, 1946, Serial No. 654,168

1 Claim. (Cl. 281—44)

1

This invention relates to artist sketch blocks, the principal object being to provide a device having a rigid base for holding a stack of sketch sheets firmly on the base against movement and in a manner to present the topmost sheet for intended use. An allied object is to arrange such a device so that the topmost sheet may be readily removed and so that the device may be readily reloaded with a fresh stack of sheets. A further object of the invention is to provide a device which will function as indicated and yet will have substantially the same over-all dimensions as the sheets and which, inclusive of its said base, will be of minimum thickness. An allied object is to arrange such a device so that it will be akin to the conventional artist sketch block both in size and general appearance, and which may be used in the same manner.

A further object of this invention is an improved artist sketch block which, unlike the conventional block, may be reloaded with a fresh stack of sheets to reconstitute a new sketch block assembly, and from which the topmost sheet may be readily removed without marring the sheets and destroying the assembly, as is the case with the conventional sketch block. A still further object is to provide a device of the character described which will receive either a single sheet or a stack of sheets of any number up to the largest stack to be accommodated, and which will hold either a single sheet or a stack of sheets firmly against movement.

For the attainment of the foregoing and such other objects as may appear or be pointed out herein, I have shown one embodiment of my invention in the accompanying drawing, wherein:

Fig. 1 is a perspective view of the improved artist sketch block;

Fig. 2 is a longitudinal sectional elevation taken on the line 2—2 of Fig. 1;

Fig. 3 and Fig. 4 are transverse sectional elevations taken on the lines 3—3 and 4—4, respectively, of Fig. 2;

Fig. 5 is a detail view, on enlarged scale, showing the construction at the narrow sides of the block; and

Fig. 6 is an exploded view, in perspective, showing the component parts of the device.

Referring to Fig. 1, it will be observed that the improved artist sketch block, which is preferably of oblong shape, resembles the conventional sketch block both in size and general appearance, and presents the topmost sketch sheet 1 (of a stack of sheets 2, Figs. 2—4) for intended use. The sheets are placed on the top surface of a rigid

base 20 made of wood, fibre, plaster or other material, and are preferably of the same length, Fig. 2, and width, Fig. 3, as the base. Encompassing the four sides of the base is a frame 10 of uniform cross-section throughout all of its four sides; this cross-section is generally of the shape of an inverted-L presenting downwardly turned flanges 11 and inwardly-directed flanges 12. Frame 10 is disposed in telescopic relation to base 20, with its downwardly-turned flanges 11 guided in sliding engagement with the sides of the base, the frame fitting on the base snugly so that the frame may be moved toward and away from the base without binding. The stack of sheets 2 is thus interposed between the top surface of the base and the inwardly-directed flanges 12 of the frame, flanges 12 overlying a small marginal border around the sheets.

The inside dimension of the downwardly-turned flange 11 of the frame and the dimension or height of the sides of the base are such that, when the largest stack of sheets to be accommodated is placed in the device, there will be sufficient area of engagement between the frame flanges and base sides to ensure that the frame and base are maintained in telescopic relation; and the mentioned dimensions are such that, with no sheets interposed, the lower edge of the downwardly-turned flanges 11 will not reach to the underside of the base, or rather, to the underside of cover plate 40, subsequently described, which forms the bottom of the improved block.

The frame, it will thus be seen, floats on the stack of sheets, in that the distance of its inwardly-directed flanges 12 from the upper surface of the base depends upon the thickness of the interposed stack. Means are provided for applying a downward force on the frame, to maintain its flanges 12 in pressing engagement with the stack of sheets, of sufficient magnitude to hold the sheets compacted and firmly so that they cannot be moved, the topmost sheet being held against movement relative to the stack and the stack being held against movement relative to the base. In the preferred embodiment, this means comprises a pair of tensile elements, shown as long helical springs 31, 31, connected at their opposite ends to plates 32, 32 mounted in the underside of base 20 for a limited extent of sliding movement. Slide plates 32, 32 are of rectangular shape and are oriented with their long dimensions parallel to the narrow sides of the base; as best seen in Fig. 2, the innermost edges of the plates are spaced an equal distance from the center of the base, the plates extend-

ing, on both sides of center, toward the ends of the base, and the outermost edges of the plates, are spaced a short distance from the respective ends of the base.

The underside of base 20 is provided with recessed guideways 22, 22, see Fig. 6, one on each side of the center, extending toward the opposite narrow sides of the base and terminating at the respective narrow sides. Guideways 22, 22, are recessed to a depth equal to the thickness of the slide plates 32, 32, so that the plates are flush with the underside of the base. A flat thin plate 40 of the same size as the base is secured to the underside of the base, with the slide plates 32, 32 received in recessed guideways 22, 22 of the base, to constitute the flush bottom of the assembled block. The guideways are separated by a central unrecessed portion 23 of the base, the edges 24, 24 of which determine the inward dimension of the guideways. Slide plates 32, 32 are each provided with a pair of long runners 35, 35 which are slidably received in long grooves 25 recessed in the underside of the base at the plate guideways 22. As best seen in Fig. 6, the central portion 23 of the base is also provided with grooves 21, 21 which extend across the entire length of the central portion and are recessed to the same depth as the grooves 25. The pair of grooves 21, 21 of the central portion are aligned with the grooves 25, so that there is presented two continuous grooves 25, 21, 25, extending parallel and longitudinally of the long dimension of the base. The tensile springs 31 are attached to the slide plates 32, 32 at their runners 35, so that the runners and intermediate springs present two continuous lines 35, 31, 35 likewise extending parallel and longitudinally and receivable in the respective continuous grooves 25, 21, 25 of the base.

In placing the pair of slide plates 32, 32 connected together by tensile springs 31, 31 in position in the underside of base 20, with the plates fitting in their respective guideways 22, 22 and separated by central portion 23 of the base, the springs are required to be stretched, being somewhat shorter in their untensioned condition than the length of central portion 23. Hence when the parts are assembled, the springs will be under tension and will maintain the slide plates 32, 32 in as close relation to each other as permitted by the central base portion 23 separating the two, the innermost edges of the slides abutting the edges 24 of the central portion.

Means are provided for connecting the pair of slide plates 32, 32 with the frame 10, for the purpose of transmitting the tensile force of the springs 31, 31 to frame 10, the transmitted force being applied thereto so as to impose a downward force on the frame which will press the frame towards base 20; the connection also serves to hold the frame on the base, and must be detachable in order that the frame may be lifted from the base when the topmost sheet is to be removed or the device relocated with a fresh stack of sheets. In the preferred embodiment illustrated in the drawings, the detachable connection is shown as comprising a web 36 of flexible material such as natural or artificial leather, textile or the like of the same length as the long dimension of the slide plates, see Fig. 6, secured to the outermost edges of the slide plates 32, 32. This securing may be made by adhesive, tacking, or the like. For obtaining better securing and better force transmission, the attached end of flexible web 36 is bifurcated to provide two flaps 33, 34, see Fig. 5, secured to the upper and lower margins,

respectively, of slide plate 32. Conveniently and as shown in Fig. 5, flexible web 36 itself is made of two pieces of material secured together to form a unitary strip except at the attached end where the ends of the two pieces of material appear as the attaching flaps 33, 34.

At its unattached end, flexible web 36 may be stiffened by a strip 37 of cardboard, fibreboard or the like extending across the width of the web. 10 The flexible web 36 including its stiffening strip 37 is made sufficiently long so that its stiffened portion will be brought adjacent to the downwardly-turned flange 11 of frame 10, as clearly shown in Fig. 5. It would be understood that stiffening strip 37 is covered by the flexible material and hidden from view; if flexible web 36 is made of two pieces of material secured together, as described above and shown in Fig. 5, stiffening strip 37 may be completely covered in the manner 15 shown. Flexible web 36 may be detachably attached to the downwardly-turned flange 11 of the frame by a pair of snap fasteners, the female element 38 of the fasteners being secured to the web 36, more particularly, to its stiffening strip 37, 20 and the male elements 18 being secured to the frame flange 11.

The length of flexible web 36 from its attachment to the slide plate 32 to the fastener elements 38, 38 is such that the slide plate 32 must be pulled 30 outwardly, against the inwardly-directed urgency of the springs 31, 31, in order that the snap elements 38, 38 may be secured to the associated elements 18, 18 of the frame; this pulling out of the slide plates 32, 32 is required even when there 35 are no sheets in the device and the frame is closest to the top surface of the base. Hence the tensile force of the springs is transmitted to the frame at all times and will thus be effective to press the frame towards the base irrespective of the number 40 of sheets interposed between the frame and base.

I claim:

An artist sketch block comprising a base upon which sheets are to be stacked and an open frame to engage above perimetrical portions of the stack 45 of sheets on all four sides thereof to hold the sheets immovably in stacked registration on the base, said base being rectangular and defined by flat side and end walls and a flat top whose width and length is the same as the width and length 50 of the sheets stacked thereon, said frame comprising opposed end and side sheet framing portions engaged with a relatively narrow width of the topmost sheet along all four edges thereof, said frame having wall portions depending down- 55 wardly from said end and side portions, the opposed depending end wall portions having their inner surfaces spaced apart for a distance equal to that of one of the dimensions of the base and of the sheets stacked thereon and the opposed 60 depending side wall portions having their inner surfaces spaced apart for a distance equal to the other dimension of the base and of the stacked sheets, whereby the frame will be held to a rectilinear movement vertical adjustment towards 65 and from the base by engagement of the inner surfaces of the depending wall portions of the frame with the opposed side and end walls of the base, to accommodate a stack comprised of sketch sheets whose number may vary within the range 70 from a single sheet to the permissible maximum, the height of said depending wall portions being no greater than the thickness of the block whereby the lowermost portions thereof will be prevented from extending below the bottom of the 75 base and releasable means for applying a down-

ward pressure to the frame sufficient to firmly hold the sheets stacked on and in registry with the base with the topmost sheet framed and held immovable for sketching said releasable means comprising a tension member connected with the 5 opposite end of the frame.
